UNITED STATES PATENT OFFICE.

KATHARINE D. HOEFLER, OF PHILADELPHIA, PENNSYLVANIA.

DESIGN FOR A MITTEN.

SPECIFICATION forming part of Design No. 27,635, dated September 7, 1897.

Application filed June 14, 1897. Serial No. 640,782. Term of patent 7 years.

To all whom it may concern.

Be it known that I, KATHARINE D. HOEFLER, a citizen of the United States, residing at the city of Philadelphia, in the county of Philadelphia and State of Pennsylvania, have invented and produced a new and original Design for a Mitten, of which the following is a specification, reference being had to the accompanying drawings, forming part hereof, in which—

Figure 1 is a top or plan view of a mitten showing my design, and Fig. 2 is a vertical sectional view through the same, these two views being deemed necessary in order to fully illustrate the design of my mitten.

The leading feature of my design of a mitten consists of its particular outline, as hereinafter pointed out by reference to the drawings, in which—

A represents the tip or point of the mitten in plan view ellipsoidal. B is one edge of the same, slightly curved outward, as at b, and inward, as at c, and terminating in a substantially straight inclined portion d. C is the

other edge of the mitten, which is concave, as at e, from the tip A is convex or bulging, as at f, and terminates in a substantially straight inclined portion g. The portions d and g are joined to a straight portion or base D.

Within the foregoing outline, consisting of the tip A, sides B and C, and base D, is arranged a kinky surface ornamentation E and F on either face of the mitten. This surface ornamentation extends only to the line h, leaving at the base of the mitten a plain field G.

Having thus described the nature of my invention, what I claim as new, and desire to secure by Letters Patent, is—

A design for a mitten, as shown and described.

In testimony whereof I have hereunto set my signature in the presence of two subscribing witnesses.

KATHARINE D. HOEFLER.
